UNITED STATES PATENT OFFICE.

JOSEPH P. FIDERIUS, OF CLEVELAND, OHIO.

PORTABLE DOORSTOP.

1,408,316.

Specification of Letters Patent. Patented Feb. 28, 1922.

Application filed September 29, 1920. Serial No. 413,579.

To all whom it may concern:

Be it known that I, JOSEPH P. FIDERIUS, a citizen of the United States, residing at Cleveland, in the county of Cuyahoga and 5 State of Ohio, have invented certain new and useful Improvements in Portable Doorstops, of which the following is a specification.

This invention relates to door stops and 10 has for its principal object to provide a portable door stop of simple and inexpensive construction which may be placed upon the floor to hold a door in its open position.

With the above and other objects in view 15 as will be readily understood, the invention will be hereinafter fully described as illustrated in the accompanying drawings and the novel features thereof will be distinctly pointed out in the appended claims.

20 In the drawings similar characters of reference are used to designate corresponding parts.

Figure 1 is a side view of a door stop constructed in accordance with my invention.

25 Fig. 2 is a plan view of same,

Fig. 3 illustrates the door stop in its expanded position when in use, and

Fig. 4 illustrates a modification.

30 Referring to the drawings, 1 represents a single piece of flat spring steel or other similar material, which serves as a base and is bent upon itself at 2, then formed into an arc 3, extends longitudinally at its forward 35 end 4 and is bent under at 5 in spaced relation thereto for receiving the free end 6 of said base. The bend over end 2 of the base 1 is adapted to rest upon the floor as is also the other bend under end 5 thus causing the 40 base to be inclined, and said forward end 4 is adapted to slide longitudinally upon the free end 6 of the base when a door as indicated at 7 is swung over the arch 3 and

depresses the same. As the square corner 8 of the free end 6 of the base rests upon 45 the floor, it tends to prevent movement of the door stop when a door is swung thereover.

In the modification illustrated in Fig. 4, the forward end of a single piece of flat 50 spring steel 9 is bent over at 10 to form a space 11, and its rear end is bent upon itself at 12, then formed into an arch 13, and its free end 14 extends longitudinally and is adapted to slide within the space 11 of 55 the forward end of said piece of flat steel.

From the above description and accompanying drawings, it is obvious that a door stop so constructed is inexpensive to manufacture due to its simplicity and is efficient 60 for holding a door in its open position.

Having fully described my invention, what I claim is:

1. In a door stop, the combination of a single piece of flat spring material bent upon 65 itself at one end, one side of the flat material being formed in an arch, and means at one of the free ends of said flat material for holding the other of said free ends in movable relation thereto, substantially as 70 described.

2. In a door stop, the combination of a base, a spring arch, the spring arch having one end fixed to the base, and the spring arch having its free end bent under the 75 base, substantially as described.

3. In a door stop, the combination of a base, a spring arch, the spring arch having one end fixed to the base, the spring arch having its free end bent under the base, 80 and the portion of the spring arch bent under the base having a corner adapted to engage the floor for preventing movement of the door stop, substantially as described.

In testimony whereof I affix my signature. 85
JOSEPH P. FIDERIUS.
